UNITED STATES PATENT OFFICE.

FRANK KRASHOWETZ, OF EDDYVILLE, IOWA.

BRAKE MECHANISM FOR MINING-CARS.

1,333,320.

Specification of Letters Patent. Patented Mar. 9, 1920.

Application filed May 14, 1919. Serial No. 297,054.

To all whom it may concern:

Be it known that I, FRANK KRASHOWETZ, subject of Austria, residing at Eddyville, Rt. #1, in the county of Monroe and State 5 of Iowa, have invented certain new and useful Improvements in Brake Mechanism for Mining-Cars, of which the following is a specification, reference being had to the accompanying drawings.

10 This invention relates to an improved brake mechanism especially adapted for old and new forms of mining cars, and one of the objects of the invention is to provide a brake mechanism applicable to such cars 15 in such a manner and constructed in such wise that the brake shoes of the brake bar may be applied to the wheels incident to the draw bars coöperating toward each other, thereby preventing the cars when in a train 20 from crowding upon one another, particularly in going down an incline.

The invention further aims to provide a 25 brake mechanism of this kind applicable to mining cars of old style construction, in connection with which bumpers are employed, the brake being actuated by the 30 operation of the bumpers, thereby preventing such cars from crowding one another in descending an incline. This style of brake mechanism will actuate on a level grade, particularly when a train of cars is being 35 brought to a stop after traveling at a rapid rate of speed, in view of the fact that when the train is in the act of being brought to a stop, the draw bars will coöperate, in other words abut each other, thereby applying the brakes.

While the design and construction at 40 present illustrated and set forth is deemed preferable, it is obvious that as a result of a reduction of the invention to a more practical form for commercial purposes, the invention may be susceptible to changes, and the right to these changes is claimed, provided they are comprehended within the 45 scope of what is claimed.

The invention comprises further features and combination of parts, as will be hereinafter set forth, shown in the drawings and 50 claimed.

In the drawings:

Figure 1 is a view in side elevation of the new style mining car, showing the improved 55 brake mechanism as applied thereto, and also showing an upwardly tilting end gate.

Fig. 2 is a bottom plan view of the car, more particularly showing the various parts of the brake mechanism.

Fig. 3 is an enlarged detail view of one pair of brake shoes and the brake bar for 60 actuating or urging the shoes toward the peripheries of the wheels.

Fig. 4 is a view in side elevation of an old style mining car, showing a slightly modified form of the brake mechanism as 65 applied.

Fig. 5 is a bottom plan view of Fig. 4.

Fig. 6 is a detail sectional view, showing one of the racks 40 and its teeth 41.

Fig. 7 is a detail view of the connections 70 between one of the bell crank levers 35 and the brake shoe actuating bar, which is carried by the side of the car, opposite the side shown in Fig. 1, said connections including the lever 73 and the rods 71 and 74. 75

Referring more especially to the drawings, 1 designates a body of a mining car, 2 the axles, and 3 the wheels mounted on the axles. Secured in any suitable manner to the bottom of the car adjacent the ends 80 thereof are the guides 4 for the draw bars 5. The guide members are recessed, as shown at 6 for the reception of the draw bars. The draw bars are provided with the usual coupling heads 7, provided with coupling pins 8, which are designed to pass through the openings of the coupling heads and engage the coupling links 9, which are provided for the purpose of coupling the adjacent cars. The draw bars are provided 90 with slots 10.

Secured to the bottom of the car is an elongated metallic strap 11 having eyes 12 at its opposite ends. Chains 13 are connected to the eyes 12, and in turn connected 95 to the eyes 14 of the inner ends of the draw bars, thereby loosely anchoring the draw bars in position.

The axles 2 are mounted in journal boxes 15 of the plates 16, which are secured in 100 any suitable manner to the bottom of the car. Cap plates 17 are bolted to the plates 16, and constitute bearings for the brake shoe actuating bar 18, which is capable of rocking in the bearing cap plates 17. This 105 brake shoe actuating bar 18 is provided with shoulders 19, to prevent axial movement of the bar, the opposite ends of which are supplied with enlargements 20, which, when the actuating bar is rocked in its bear- 110

ings, coöperate between the brake shoes, in order to spread them and cause them to contact with the peripheries of the car wheels. A downwardly extending arm 21 is carried by the brake shoe actuating bar 18, and connected to the end of this arm is a coil spring 22. The other end of the coil spring is connected at 23 to a lug of one of the journal boxes. By means of this 10 spring the brake shoe actuating bar is put under tension.

Pivoted at 24 between arched plates 25 and the bottom of the car adjacent the opposite ends thereof are levers 26. To 15 the outer end of one of the levers 26 a chain 27 is connected. This chain 27 is in turn connected to a rod 28. The other end of the rod 28 is connected at 30 to an upwardly extending arm 31 of the rocking 20 brake shoe actuating bar. The inner ends of both levers 26 extend loosely into the slots 10 of the draw bars. To the outer end of the other lever 26 a rod 71 is connected. This rod is in turn connected at 72 to the upper 25 end of a lever 73, which is pivoted to the side of the car. The lower end of the lever 73 has connected thereto a rod 74, which in turn is connected to a second upwardly extending arm 31 of the rocking brake shoe 30 actuating bar. It is to be noted that when pressure is applied to the draw bars incident to the cars crowding toward each other, the levers 26 will be tilted on their pivots, thereby pulling upon the chain 27 and the 35 rod 28 and upon the rod 71. The rod 71 tilts the lever 73 which pulls the rod 74, at the same time the rod 28 is pulled, thereby rocking the actuating bar 18, and owing to the enlargements 20 becoming positioned horizontally 40 between the brake shoes, the brake shoes are urged toward and into coöperation with the peripheries of the car wheels.

The lever 32 is pivoted at 33 to one side of the car near one end. The lower end of 45 the lever 32 has connected thereto a chain 34, which in turn is connected to the rod 28. Bell crank levers 35 are pivoted at 36 to the opposite sides of the car near the diagonal opposite ends thereof. To one of said bell 50 crank levers 35 a rod 37 is connected, and which in turn is connected to the lever 32. The other bell crank lever 35 is linked or connected as shown at 75 to the lever 73. It is obvious that by tilting either one or 55 both of the bell crank levers by foot pressure in the direction of the arrow α , as indicated in Fig. 1, the levers 32 and 73 may be tilted upon their pivots imparting a pulling action upon the rods 28 and 74, so as 60 to rock the brake shoe actuating bar 18. Of course, when this bar is rocked, its enlargements will become positioned horizontally between the brake shoes and spread them sufficiently to urge them toward the peripheries of the car wheels. Suitable racks 65

are secured to the opposite sides of the car in diagonal opposite relation to each other, and these racks are provided with teeth 41, with which the long arms of the bell crank levers may coöperate, to hold the bell crank 70 levers in different adjusted positions, and consequently hold the brake shoes applied. It is obvious that when the actuating bar 18 is rocked, the coil spring 22 is put under tension, sufficiently to turn the bar 18 to its 75 normal position, and since the arms 31 are connected to the rods 28 which in turn are connected to the levers 26, the rocking bar 18 is limited in its normal position.

The brake shoes 43 are pivotally mounted 80 on the sides of the car upon pins 44. The brake shoes, each consist of an elongated metallic strip bent upon itself to form the loop 45, for the reception of the pin 44. The opposite portions of the strip are 85 brought together and bolted as at 47. The lower parts of the opposite portions of the strip extend downwardly, and are bent at 48, the bent portions extending toward each other, and again bent at 49 and 50. Beyond 90 the bends 50 the opposite portions of the strip extend from each other, and are bent at 51. The portions 53 of the strip beyond the bends 51 are curved concentrically with the peripheries of the car wheels, and owing to the extremities of these parts 53 being free and unattached, the parts 53 are yieldable. It is to be noted that the lower parts 95 of the opposite portions of the strip, and including the parts 53 constitute the brake 100 shoes. When the enlargements of the actuating bar 18 become positioned horizontally causing the brake shoes to spread, their parts 53 are urged yieldably in contact with the peripheries of the car wheels, 105 thereby offering sufficient friction thereon, to brake the car wheels, hence preventing the cars from crowding each other, either on a level or down-grade. It is obvious that when the cars are being pulled up-grade, the 110 draw bars operate to actuate the levers 26, which in turn restores the actuating bar 18 to its normal position, the spring 22 assisting in this regard, hence allowing the brake shoes to release their frictional contact with the peripheries of the car wheels. If desired, the brakes of the cars can be applied manually, by operating the bell 115 crank levers.

A bail member 54 has its opposite arms 120 55 pivoted at 56 to the opposite sides of the car. A second bail member 57 has its arms integrally connected to the arms of the bail member 54, so that they extend angularly relatively to the arms 55. A tail end 125 gate 58 is fixed or connected at 59 to the bail members, and by means of the bail members, the tail end gate of the car body is held in position at one end of the car. Obviously the bail members may be tilted 130

upwardly, so that the tail gate may be raised, allowing the contents of the car to be dumped or shoveled out.

Referring to Figs. 4 and 5, it is to be noted that a modified form of brake mechanism is applied to an old style miner's car. This brake mechanism is considerably similar to the mechanism shown in Figs. 1 and 2, with the exception that a single actuating bar 18 is dispensed with, and in lieu thereof a pair of actuating bars 60 is employed. These rocking bars 60 are axially alined, and have their outer ends provided with enlargements 62, similar to those shown in Figs. 1 and 2. The inner ends of the rocking bars 60 are supplied with downwardly extending arms 63, to which the rods 64 and 65 are connected. The rods 64 are in turn pivotally connected to the levers 66 which are pivotally mounted at 67 to the bottom of the car. Suitable bumper members 68 are mounted in bearings of the opposite ends of the car, that is in diagonal relation to each other. The rods 69 of these bumper members are connected pivotally to the levers 66. The rods 65 at their outer ends terminate in bumper members 70, which are mounted in bearings of the opposite ends of the car. It may be observed that by the actuation of the bumper members, that is one set of bumper members contacting with a similar set on an adjacent car, will impart rocking motions to the rocking bars 60, and owing to their enlargements being positioned between the brake shoes, the shoes will be urged in yieldable contact with the peripheries of the car wheels. The mechanism in Figs. 4 and 5 may also be actuated manually, by means of bell crank levers and connections similar to those previously described, hence it is believed unnecessary to repeat the designations and the operation of such parts.

The invention having been set forth, what is claimed as new and useful is:

1. In a brake mechanism, the combination with a pair of adjacent car wheels, of a brake member having brake shoes provided with yieldable parts, and means for spreading the brake shoes, whereby the yieldable parts may be urged yieldably in frictional contact with the peripheries of the car wheels, and means actuated by the crowding action of adjacent cars to actuate the first means for applying the brake shoes, said last mentioned means comprising a transversely disposed rocking bar, tensioning means therefor, levers having connections with the rocking bar, and draw bars adapted to be actuated by the jamming action of the draw bars with adjacent draw bars and connected to the levers for oscillating them.

2. In a brake mechanism, the combination with a pair of adjacent car wheels, of a brake member having brake shoes provided

with yieldable parts, and means for spreading the brake shoes, whereby the yieldable parts may be urged yieldably in frictional contact with the peripheries of the car wheels, and means manually actuated for operating the first means, said last mentioned means comprising a rocking bar having enlargements positioned between the brake shoes for spreading them, tensioning means for the rocking bar, levers pivoted on the sides of the car having connections with the rocking bar, and manually operated bell crank levers connected to the first mentioned levers to actuate the rocking bar.

3. In a brake mechanism, the combination with a pair of adjacent car wheels, of a brake member pivotally mounted on the side of the car and provided with downwardly depending yieldable parts adapted to be separated, the lower portions of the parts being bent upon themselves and having their end portions terminating in yieldable brake shoes to yieldably frictionally contact with the peripheries of the adjacent car wheels, and a spring tensioned member having an enlargement positioned between the depending separable parts for spreading them, whereby the brake shoes may be applied frictionally on the adjacent peripheries of the car wheels.

4. In a brake mechanism, the combination with a pair of adjacent car wheels, of a brake member provided with depending yieldable parts adapted to be forced apart, the lower ends of the yieldable parts terminating in yieldable brake shoes, said brake member being pivoted to the side of the car body, whereby the depending parts are positioned between the peripheries of the car wheels, with the shoes adjacent to and adapted to be applied to the peripheries of the car wheels, when said parts are separated, said brake member being constructed from a single piece of metal, bent to form the opposing depending yieldable parts and the brake shoes.

5. In a brake mechanism, the combination with a pair of adjacent car wheels, of a brake member provided with depending yieldable parts adapted to be forced apart, the lower ends of the yieldable parts terminating in yieldable brake shoes, said brake member being pivoted to the side of the car body, whereby the depending parts are positioned between the peripheries of the car wheels, with the shoes adjacent to and adapted to be applied to the peripheries of the car wheels, when said parts are separated, said brake member being constructed from a single piece of metal, bent to form the opposing depending yieldable parts and the brake shoes, and means acting between the brake shoes to separate the depending parts, whereby the shoes may be applied to the wheels.

6. In a brake mechanism, the combination with a pair of adjacent car wheels, of a brake member constructed from a single strip of spring metal, bent upon itself midway its ends, thereby forming a pivoting eye, means extending through the eye to pivot the member to the side of the car, means to secure the opposing bent portions of the sheet metal to each other at a point beyond the pivoting eye, the portions of the metal beyond the securing means diverging downwardly a short distance, then inwardly at acute angles, then directly downwardly and in parallelism, thereby constituting opposing depending and yieldable parts adapted to be forced apart, the downward parallel portions of the depending parts terminating in yieldable brake shoes concentric with the car wheels, whereby upon separating the depending parts, yieldable brake shoes may be applied yieldably and frictionally in contact with the peripheries of the car wheels, and means for forcing apart the depending parts to apply the brake shoes.
7. In a brake mechanism, the combination with a pair of adjacent car wheels, of a brake member having depending brake shoes adapted to be forced apart, means for

suspending the member from the side of the car, whereby the shoe is positioned between the peripheries of the car wheels, of a rocking bar having enlargements at either end positioned between the brake shoes, whereby upon rocking the bar, the shoes may be applied frictionally in contact with the peripheries of the car wheels, means for tensioning the rocking bar to hold the narrow portions of the enlargements normally engaging between the shoes, levers pivoted upon the bottom of the car body at diagonal opposite portions thereof, one end of each of said levers having a rod connection with the brake shoe actuating bar, draw bars connected to said levers, and adapted to be actuated by the crowding action of the draw bars and being connected to said levers for actuating them, and means co-operatively connected with said connections, and adapted to be manually manipulated, for applying the brake shoes on the peripheries of the car wheels.

In testimony whereof I hereunto affix my signature in the presence of two witnesses.

FRANK KRASHOWETZ.
